(57) **CLAIM**

The ornamental design for a hair dryer as shown and described.

DESCRIPTION

The patent or application file contains at least one drawing executed in color. Copies of this patent or patent application publication with color drawing(s) will be provided by the Office upon request and payment of the necessary fee.

1. Hair dryer

1.1 is a perspective view;

1.2 is another perspective view;

1.3 is a left side elevation view;

1.4 is a rear view;

1.5 is a front view;

1.6 is a top view;

1.7 is a bottom view; and

1.8 is a right view.

The portions of the design shown in the color red depict portions that are for illustrative purposes only and form no part of the claimed design.
